SHOWCASE

Arthur Eugene Claussen, Jr., Oakmont, Pa., assignor to E. F. Kemp, Corp., Somerville, Mass., a corporation of Massachusetts

Application April 20, 1950, Serial No. 9,347

Term of patent 14 years

(Cl. D80—11)

To all whom it may concern:

Be it known that I, Arthur Eugene Claussen, Jr., a citizen of the United States of America and a resident of Oakmont, in the county of Allegheny, Pennsylvania, have invented a new, original, and ornamental Design for a Showcase, of which the following is a specification, reference being had to the accompanying drawings, forming part thereof.

Figure 1 is a perspective view of a showcase embodying my new design.

Figure 2 is a side elevation of the showcase shown in Figure 1.

Figure 3 is a top plan view of the showcase shown in Figure 1.

The back of the showcase is plain.

I claim:

The ornamental design for a showcase, as shown and described.

ARTHUR EUGENE CLAUSSEN, JR.
